US00D891604S

(12) **United States Design Patent** (10) Patent No.: **US D891,604 S**
(45) Date of Patent: **** Jul. 28, 2020**

(54) **ROOF VENT ASSEMBLY**(71) Applicant: **Gregory S. Daniels**, Santa Rosa, CA
(US)(72) Inventor: **Gregory S. Daniels**, Santa Rosa, CA
(US)(**) Term: **15 Years**(21) Appl. No.: **29/618,892**(22) Filed: **Sep. 25, 2017****Related U.S. Application Data**

(63) Continuation-in-part of application No. 29/546,178, filed on Nov. 19, 2015, now Pat. No. Des. 841,797.

(51) LOC (12) Cl. .... **23-03**(52) U.S. Cl. USPC .... **D23/393**(58) **Field of Classification Search**USPC **D23/387, 354, 419, 393**
CPC **F24F 7/00; F24F 7/02**

See application file for complete search history.

CLAIM

The ornamental design for a roof vent assembly, as shown and described.

DESCRIPTION

FIG. 1 is a top perspective view of a roof vent assembly; FIG. 2 is a top view of the roof vent assembly of FIG. 1; FIG. 3 is a bottom view of the roof vent assembly of FIG. 1; FIG. 4 is a bottom view of an embodiment of the roof vent assembly of FIG. 1 without a lower screen; FIG. 5 is a front view of the roof vent assembly of FIG. 1; FIG. 6 is a rear view of the roof vent assembly of FIG. 1; FIG. 7 is a right side view of the roof vent assembly of FIG. 1, with the left side view being a mirror image of FIG. 7; FIG. 8 is a top perspective view of an embodiment of the roof vent assembly of FIG. 1, the only difference being the configuration of the bottom flange; FIG. 9 is a top view of the roof vent assembly of FIG. 8; FIG. 10 is a bottom view of the roof vent assembly of FIG. 8;

FIG. 11 is a bottom view of an embodiment of the roof vent assembly of FIG. 8 without a lower screen;

FIG. 12 is a front view of the roof vent assembly of FIG. 8; FIG. 13 is a rear view of the roof vent assembly of FIG. 8; FIG. 14 is a right side view of the roof vent assembly of FIG. 8, with the left side view being a mirror image of FIG. 14; FIG. 15 is a top perspective view of another embodiment of the roof vent assembly of FIG. 1, without a solar panel; FIG. 16 is a top view of the roof vent assembly of FIG. 15; FIG. 17 is a bottom view of the roof vent assembly of FIG. 15;

FIG. 18 is a bottom view of an embodiment of the roof vent assembly of FIG. 15 without a lower screen;

FIG. 19 is a front view of the roof vent assembly of FIG. 15; FIG. 20 is a rear view of the roof vent assembly of FIG. 15; FIG. 21 is a right side view of the roof vent assembly of FIG. 15, with the left side view being a mirror image of FIG. 21; FIG. 22 is a top perspective view of a second embodiment of the roof vent assembly of FIG. 15, the only difference being the configuration of the bottom flange;

FIG. 23 is a top view of the roof vent assembly of FIG. 22; FIG. 24 is a bottom view of the roof vent assembly of FIG. 22;

FIG. 25 is a bottom view of an embodiment of the roof vent assembly of FIG. 22 without a lower screen;

FIG. 26 is a front view of the roof vent assembly of FIG. 22; FIG. 27 is a rear view of the roof vent assembly of FIG. 22; and,

FIG. 28 is a right side view of the roof vent assembly of FIG. 22, with the left side view being a mirror image of FIG. 28;
